PROTECTIVE MAT FOR STOVES

Walter Chester, Center Line, Mich.

Application August 21, 1939, Serial No. 291,229

4 Claims. (Cl. 126—221)

This invention relates to mats for stoves, and its general object is to provide a mat that is primarily designed for protecting enameled or like finished tops of the oven or other parts of cooking appliances, against becoming cracked, scratched or otherwise damaged by the application of a cooking vessel thereto, in that my mat not only acts to support the vessel elevated from the finished surface, but allows for the free circulation of air between the mat and surface, as well as below the vessel, thereby preventing thermal shocks caused by placing a cold vessel upon the heated surface, which generally results in cracking the finish and in any event discolors the same, but by the use of my mat the finish is maintained free from damage.

A further object is to provide a protecting mat for the purpose set forth, that is preferably finished with porcelain on steel, and is not only capable of protecting the finish of the stove, but adds materially to the appearance of the latter.

Another object is to provide a protecting mat that is simple in construction, inexpensive to manufacture, and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a top plan view of the mat which forms the subject matter of the present invention.

Figure 2 is a side view, with parts in section.

Figure 3 is a sectional view taken approximately on line 3—3 of Figure 1, looking in the direction of the arrows.

Figure 4 is a sectional view taken approximately on line 4—4 of Figure 1.

Referring to the drawing in detail, it will be noted that my mat is constructed substantially in the form of a grate, to include relatively narrow elongated channelled end bars 1 having the open portions facing downwardly and the bars are of inverted substantially U-shape in cross section to provide flat upper walls and straight parallel side walls having outwardly flared lower edges, as best shown in Figure 4. Frictionally fitting within the channels of the end bars and at the ends thereof are rectangular shaped blocks

2 of cushioning material, such as rubber or the like and which may be secured therein by any suitable means, but in any event are of a size to extend below the lower edges of the side walls to provide feet for supporting the mat a considerable distance above the surface to be protected thereby.

Secured to and bridging the end bars 1 at equidistantly spaced intervals with respect to each other, are parallel ribs 3 which are likewise of inverted substantially U-shape in cross section for the major portion of their length, to provide flat upper walls and straight parallel side walls, the latter being outwardly flared in curved formation adjacent their ends to merge into the flat upper walls in straight formation to provide flat ends 4 for the ribs, that are welded or otherwise fixed to the upper walls of the end bars 1.

The ribs may be formed from a single sheet of steel so that the ends thereof are integral, as shown, and in that event the sheet will be slit and shaped to provide the ribs. However, the ribs may be formed from individual strips of steel, with the flat ends thereof disposed in abutting or edge to edge engagement. The lower edges of the ribs extend a considerable distance above the lower edges of the bars, as best shown in Figure 4, so that a considerable space will be provided between the ribs and the surface protected by the mat.

The bars are likewise made from steel and both the bars and the ribs are coated with porcelain or other suitable material which is not subject to being cracked or discolored by heat, or scratched by the application of a cooking vessel or the like upon the mat.

From the above description and disclosure in the drawing, it will be obvious that I have provided a mat that can be set upon an enameled surface of the top of an oven or other part of a cooking appliance, for receiving cooking vessels, such as pots and pans, to protect the surface, as and for the purpose previously set forth.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A protective mat for cooking appliances, comprising a pair of channelled end members having their open portions lowermost, channelled

ribs secured to and bridging the end members in spaced parallel relation to each other and having flat upper walls providing a supporting surface for cooking vessels, and cushioning means 5 providing feet frictionally fitting within the end members at the ends thereof and extending below the same for elevating the mat above the surface to be protected thereby.

2. A protective mat for cooking appliances, 10 comprising a pair of channeled end members having their open portions lowermost and provided with flat upper walls, channeled ribs bridging the end members in spaced parallel relation to each other and having flat ends integral with 15 each other and fixed to the flat upper walls, said ribs having flat upper walls providing a supporting surface for cooking vessels, and cushioning means providing feet frictionally fitting within the end members at the ends thereof and 20 extending below the same for elevating the mat above the surface to be protected.

3. A protective mat for cooking appliances, comprising a pair of inverted substantially U- 25 shape channeled end members having their open portions lowermost and provided with flat upper walls and parallel side walls outwardly flared along their lower edges, channeled ribs bridging

the end members in spaced parallel relation to each other and having flat ends fixed to the flat upper walls, cushioning means providing feet secured within the end members at the ends thereof and extending below the same for elevating the mat above the surface to be protected thereby, and said end members and ribs being formed from steel coated with porcelain. 5

4. A protective mat for cooking appliances, comprising a pair of end bars of inverted substantially U-shape in cross section having their open portions lowermost and provided with flat upper walls and parallel side walls outwardly flared along their lower edges, channeled ribs bridging the end bars in spaced parallel relation 15 to each other and having flat upper walls and parallel side walls, the latter walls being outwardly flared in curved formation to provide with the upper walls of the ribs flat ends therefor fixed to the flat upper walls of the bars, 20 blocks formed from cushioning material and providing feet secured within the end members at the ends thereof and extending below the same for elevating the mat above the surface to be protected thereby, and said bars and ribs 25 being formed from steel coated with porcelain.

WALTER CHESTER.
